UNITED STATES PATENT OFFICE.

JOHN N. REES, OF LOUISVILLE, KENTUCKY.

SASH-LOCK.

SPECIFICATION forming part of Letters Patent No. 680,811, dated August 20, 1901.

Application filed October 20, 1900. Serial No. 33,765. (No model.)

To all whom it may concern:

Be it known that I, JOHN N. REES, a citizen of the United States, residing at Louisville, in the county of Jefferson and State of Kentucky, 5 have invented a new and useful Sash-Lock, of which the following is a specification.

This invention relates to sash-locks, and has for one object to automatically lock both sashes when they are in their closed positions 10 and at the same time to permit of the independent opening of the sashes from the interior of the building. It is furthermore designed to provide for conveniently applying the present lock to sashes already in position 15 without altering the same beyond setting the lock into one of the side rails of the upper sash.

Another object resides in the provision of means for conveniently throwing the lock out 20 of operation and also to provide for tripping the lock, so as to bring it into operation by the closing movement of the sashes.

With these and other objects in view the present invention consists in the combination 25 and arrangement of parts, as will be hereinafter more fully described, shown in the accompanying drawings, and particularly pointed out in the appended claims, it being understood that changes in the form, proportion, size, and minor details may be made 30 within the scope of the claims without departing from the spirit or sacrificing any of the advantages of the invention.

In the drawings, Figure 1 is a front elevation of a portion of two window-sashes having the present lock applied thereto. Fig. 2 is a transverse sectional view thereof. Fig. 3 is a similar view showing the lock in its inoperative position. Fig. 4 is a transverse 35 sectional view showing a modified arrangement of the lock. Fig. 5 is a detail elevation of the opposite side of the swinging latch. Fig. 6 is a detail transverse sectional view taken on the line 6-6 of Fig. 2.

40 Corresponding parts are designated by like characters of reference in all of the figures of the drawings.

Referring to the drawings, 1 and 2 designate, respectively, the upper and lower sashes 45 of an ordinary window-frame, said sashes being hung by means of pulley-weights or otherwise, as may be desired.

As shown in Figs. 1, 2, and 3 of the drawings, the upper sash has its left-hand side rail provided with a mortise or socket in its 55 front face and located adjacent to the lower or meeting rail thereof for the reception of the casing 3 in the form of a box, having its front edge provided with a longitudinal slot 4, through which the swinging latch 5 is designed to project and overhang the meeting-rail of the lower sash, as indicated in Fig. 2, so as to lock both sashes against movement in opposite directions. This latch is pivotally mounted at its upper end upon an internally-screw-threaded stud 6, which projects laterally from about midway of the length of one side of the lock-casing. The opposite side 7 of the casing is removable and is held in place by means of a screw-fastening 8, 70 which passes through said side and into the internally-screw-threaded stud, whereby the latch is also prevented from being displaced from its pivotal support. One face of the latch is provided with a socket or recess surrounding its pivotal support and is designed for the reception of a coiled spring 9, the inner end of which is secured in a transverse slit or groove formed across the outer end of the stud 6, as indicated at 10, and its opposite end being secured to a pin 11, projecting from the back of the recess, whereby the latch is provided with a spring tension to normally hold the same in a pendent position. 75

It will be observed that the lower free end 80 of the latch normally projects outwardly through the slot in the casing and rests against a stop pin or shoulder 12, projecting from the fixed side of the casing. To hold the latch against accidental outward and upward movement, there is provided a pivotal catch 13, mounted upon the inner side of the casing and having its free end arranged beneath the free end of the latch and provided with a suitable catch-head 14 to engage a 85 shoulder or projection 15, formed upon the lower end of the latch, preferably by means of a recess. A suitable spring 16 is interposed between the back of the catch or detent to yieldingly hold it in engagement with 90 the latch. 95

In order that the latch may be conveniently freed from the catch or detent, there is provided a trip-pin 17, which works diagonally 100

across the latch and in a slot formed there-through and opening into the recess, whereby the projection 15 is formed, so that by forcing the pin downwardly it will push the de-
 tent out of engagement with the latch, where-
 by the latter is freed and may be swung ver-
 tically out of the path of the lower sash to
 permit of the latter being raised. This trip-
 pin is provided with an intermediate slot or
 notch 18 for the reception of a transverse
 stop-pin 19, carried by the latch, so that the
 ends of the slot or notch may engage the pin,
 and thereby prevent endwise displacement
 of the trip-pin. A suitable operating-head
 20 is provided for the outer end of the trip-
 pin, said head being beveled upon its outer
 side, so as to lie flush with the outer edge of
 the latch, the latter being provided with an
 angular notch 21 for the reception of the head
 20 and is slightly longer than the latter, so
 as to provide for the movement of the pin.
 When the latch is freed from the detent, it is
 swung upwardly and into the interior of the
 casing, as shown in Fig. 3, in which position
 it is held by means of a bowed spring 22, ex-
 tending transversely across the upper end of
 the casing and designed to frictionally bear
 against the inclined end of the latch, and
 thereby hold the latter against the tension of
 the coiled spring. In this inoperative position
 of the latch the upper and lower sashes
 may be opened without interference by the
 latch.

To automatically trip the latch and swing
 it into its operative position, there is pro-
 vided a rocking cam-shaped trip 23, as best
 shown in Fig. 5, which is mounted upon that
 side of the latch which is opposite the coiled
 spring. The upper rounded end of the latch
 40 is reduced upon the cam side thereof, so that
 the trip may lie flush with the face of the
 latch, the recess thus formed having a trans-
 verse shoulder 24, extending inwardly from
 the front edge of the latch, and a diagonal
 shoulder 25, inclining from the inner end of
 the transverse shoulder toward the inner
 lower corner of the latch. The cam-trip has
 its upper edge rounded to correspond to the
 latch, while its lower edge is straight, so as
 45 to bear against the transverse shoulder 24,
 and thereby interlock the latch and the trip.
 It will be understood that the trip is provided
 with an opening 26, whereby it is mounted
 upon the stud 6, and its longest portion pro-
 jects outwardly through the opening in the
 50 casing, so as to lie in the path of the meet-
 ing-rail of the lower sash. A leaf-spring 27
 is interposed between the straight inner edge
 of the trip and the inclined shoulder, so as
 55 to yieldingly hold the cam in its extended po-
 sition. By reason of the inclined wall 25 the
 recess is enlarged, so that the trip may be
 swung inwardly, as indicated by dotted lines,
 so that the rear edge may be free from pro-
 60 jections.

From the foregoing description it will be

apparent that when the latch is thrown up-
 wardly into its inoperative position the lower
 sash may be freely raised, as its meeting-rail
 will strike the rounded or inclined edge of
 the trip, and thereby force it inwardly into
 its recess, after which the trip will spring
 outwardly again under the influence of the
 spring 27. When the sash is lowered, the
 meeting-rail will strike the straight edge of
 the trip, thereby forcing the opposite end of
 said edge against the transverse shoulder 24,
 whereby the trip and the latch are inter-
 locked, and as the sash is lowered the latch
 will be drawn out of engagement with the
 spring 22 and finally thrown downwardly
 into its operative position by means of the
 coiled spring. It is preferable to provide
 the upper side of the meeting-rail of the lower
 sash with a wear-plate 28 to project at the
 inner edge of the rail and engage the rock-
 ing trip of the lock and to strike against the
 latch in its locked position, so as to prevent
 the wooden rail from being worn and dam-
 aged. As shown in Fig. 3, the plate rests
 upon a weather-strip 29, and the latter is cut
 away or provided with a notch to accommo-
 date the projecting portion of the trip-cam.

When the sashes are locked and it is de-
 sired to unlock the same, it is merely neces-
 sary to press downwardly upon the head of
 the trip-pin 17, so as to disengage the detent,
 whereby the latch is free to be swung up-
 wardly to the position shown in Fig. 3 of the
 drawings.

The form of the lock just described is de-
 signed for application to sashes in the manu-
 facture thereof, as the mortises can then be
 conveniently formed, and the case has the
 opposite terminal attaching-ears 29 located
 105 at the front of the casing, so as to be secured
 to the outer side of the sash-rail. In order
 to accommodate the lock to sashes already
 mounted in their frames, the attaching-ears
 are placed upon the fixed side of the casing,
 110 as shown in Fig. 4, whereby the lock may be
 secured to the inner edge of a side rail adja-
 cent to the pane of glass, the other parts of
 the device being precisely the same as here-
 inbefore described.

What is claimed is—

1. The combination with opposite window-sashes, of a sash-lock carried by one of the sashes, and provided with a locking member, which has opposite operative and inoperative positions, and means for automatically tripping the movable locking member from its inoperative position to its operative position by contact of said means with the other sash, said means being carried solely by the movable locking member and arranged in the path of the closing movement of the said other sash when the movable locking member is in its inoperative position, the said means also being fixed against independent motion in the direction of the operative position of the locking member, and being elas-

tically yieldable in the opposite direction, whereby the said other sash may be opened without interfering with the locking member.

2. A sash-lock, comprising a vertically swinging latch, which has its locked position at its lowermost limit, and its unlocked position at its uppermost limit, means for detachably holding the latch in its unlocked position, an upwardly and inwardly elastically yieldable sash-engaging trip pivoted to the latch and projected laterally therefrom, and means for locking the trip against independent movement downwardly upon the latch.

3. A lock, comprising a movable locking member, which has its locked and unlocked positions at the opposite limits of its movement, an elastically-yieldable trip pivoted to the latch, and having its outer free end projected laterally beyond the front side thereof in the unlocked position only of the latch, and a stop-shoulder carried by the latch, located between the inner end of the pivotal trip and the free end of the latch, and normally in engagement with said inner end of the trip, whereby the latter is locked against independent motion in one direction and is free to yield in the opposite direction.

4. A sash-lock, comprising a swinging latch, which has its locked and unlocked positions at its opposite limits, and swings through an arc of substantially one hundred and eighty degrees, one end of the latch having a pivotal support, and its opposite free extremity forming the sash-engaging locking part, and a sash-engaging trip pivotally mounted upon the latch intermediate of its ends, said trip being elastically yieldable inwardly and toward the free end of the latch, and interlocked with the latch against independent movement thereon in the opposite direction.

5. In a sash-lock, the combination with a casing having a longitudinal slot in its outer side, of a swinging latch having its inner end pivoted within the casing and substantially midway between its opposite ends, and having a swing through the slot into the opposite end portions of the casing, the locked and unlocked positions of the latch being at opposite limits thereof, the free end of the latch being projected laterally outward through the slot in the locked position thereof, and lying wholly within the casing in its unlocked position, and a sash-engaging trip pivoted upon the latch and normally projected at one side thereof, said trip being elastically yieldable toward the free end of the latch, and interlocked with the latch against independent movement in the opposite direction, the trip being projected laterally outward through the slot of the casing in the unlocked position of the trip, and located between the latch and the back of the casing in the locked position of the latch.

6. A sash-lock, comprising a swinging latch, a pivotal support therefor, said latch having one side recessed about the pivotal support, the inner wall of the recess having a trans-

verse stop-shoulder portion and an outwardly inclined portion, a trip received within the recess and pivotally mounted upon the pivotal support of the latch, one end of the trip being in engagement with the stop-shoulder in the inoperative position of the latch, and its opposite free end projecting laterally beyond the edge of the latch, and a spring interposed between the free portion of the trip and the inclined shoulder.

7. A sash-lock, comprising a swinging latch, a detachable latch-holding device at the operative limit of the latch, means for disengaging the same, a detachable latch-holding device at the opposite inoperative limit of the latch, and a window-sash-engaging trip carried by the latch and projected into operative position only when the latch is in its inoperative position.

8. In a lock, a movable locking member, a holding device therefor, which is mounted independently of the part to be locked and engaged with the locking member in its locked position only, and means for disengaging the holding device from the locking member, and carried solely by the latter.

9. A sash-lock, comprising a swinging latch, having a notch in its free end, and an open-ended slot opening into said notch, a pivotal latch-holding detent for engagement with the notch, and a slidable pin working in the slot, one end of the pin extending into the notch, and the opposite end having an operating-head or finger-piece.

10. In a sash-lock, the combination with a casing, having a longitudinal slot or opening, of a swinging latch having one end pivoted intermediate of the ends of the casing, a notch in its free end, and a diagonal slot opening at one end through the outer edge of the latch and at the opposite end into the notch, a latch-holding detent pivoted within the casing and normally in engagement with the notch, and a longitudinally-slidable detent-disengaging pin working in the slot, and having its outer end provided with a finger-piece received within a recess formed in the outer edge of the latch.

11. In a sash-lock, the combination with a casing, of a longitudinally-swinging latch pivoted intermediate of the ends of the casing, a spring-actuated latch-holding detent at one end of the casing, a slidable detent-disengaging device mounted upon the latch, and having an exposed finger-piece, and a yieldable latch-holding device mounted at the opposite end of the casing.

12. In a sash-lock, the combination with a casing, having an intermediate pivot-stud, of a swinging latch mounted upon said stud, and provided in opposite sides with recesses surrounding the stud, a coiled spring received in one of the recesses and connected at opposite ends to the stud and the latch, a trip received within the other recess and pivotally mounted upon the stud, one wall of the recess forming a stop-shoulder in engage-

ment with one end of the trip, a spring inter-
posed between the opposite end of the trip
and the adjacent wall of the recess, a latch-
holding device at one end of the casing,
5 means for disengaging the detent carried by
the latch, and detachable latch-holding means
at the opposite end of the casing.

In testimony that I claim the foregoing as
my own I have hereto affixed my signature in
the presence of two witnesses.

JOHN N. REES.
